(57) **CLAIM**

The ornamental design for a hand rail for toilet, as shown and described.

DESCRIPTION

FIG. 1 is a perspective view of a hand rail for toilet shown in condition of use with a toilet showing our new design;

FIG. 2 is a left side view thereof;

FIG. 3 is a right side view thereof;

FIG. 4 is a top plan view thereof; and,

FIG. 5 is a front elevational view thereof.

The broken line showing of toilet is for illustrative purposes only and forms no part of the claimed design.
